UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

PACKING STRUCTURE.

1,299,368.

Specification of Letters Patent.

Patented Apr. 1, 1919.

Application filed August 31, 1915. Serial No. 48,224.

To all whom it may concern:

Be it known that I, PATRICK H. MACK, a citizen of the United States, residing at Bradford, in the county of McKean and State of Pennsylvania, have invented certain new and useful Improvements in Packing Structures, of which the following is a specification.

This invention relates to packing structures and more particularly to structures employed in the packing of wells.

While the invention is designed more particularly for use in connection with well packers, plugs, etc., and is particularly described herein in connection therewith, the general principles of the invention may be employed in other connections, the invention not being limited to this particular use.

Well packing devices, under present practice, are of different types, the packing element or member generally employed being in the form of an elongated cylinder usually made of rubber, the cylinder being mounted on an inner unyielding member such as a tube, and being designed to be expanded into contact with the wall of the well at the proper point therein. As the packer must have a free movement within the well in reaching the desired point, the packing element or member has a normal thickness insufficient to bridge the space between the tube and the well walls. To produce the packing relation between the tube and well wall, it is the practice to expand the packing member by movements of a compressing element in the direction of length of the tube.

In expanding the member to provide this contact with the walls of the well, there is a tendency to produce a space between the packing member and the tube through the bulging effect produced by the action of the compressing member. This, obviously, results in decreasing the ability of the packing member to resist leakage between the member and the wall of the well, since the resistance of the packing member itself becomes variable through the absence of a rigid support between the packing member and the tube.

The present invention is designed to overcome these difficulties by producing a zone or zones of substantially uniform resistance within the packing member intermediate its ends, this result being obtained by the employment of one or more rigid members positioned by the compression action of the pack-

ing member itself, such compressing action tending to move the rigid member or members in the direction of least resistance until the resistance is built up to approximately balance the pressure applied. This effect is produced regardless of the conditions of service, since the proper building up of resistance action is provided through the effect placed on the packing member during its compression. As a result, a zone or zones of substantially uniform resistance are produced, the packer structure within each zone being solid between the well wall and the supporting tube, thereby effectually preventing any inward yielding of the packing member sufficient to provide any material leakage within the zonal-contacting area.

To these and other ends, the nature of which will be readily understood as the invention is hereinafter disclosed, said invention consists in the improved construction and combination of parts as hereinafter fully described, illustrated in the accompanying drawing, and more particularly pointed out in the appended claims.

In the accompanying drawing, in which similar reference characters indicate similar parts in each of the views,

Figure 1 is an enlarged sectional view showing a simple arrangement of parts for providing the desired result, the parts being shown in unexpanded position.

Fig. 2 is a similar view showing the packing expanded.

Fig. 3 is a vertical sectional view of one form of well packer having the present invention applied thereto.

Fig. 4 is a similar view of a different type of packer showing the invention applied thereto.

Referring more particularly to Figs. 1 and 2, representing a simple way in which the present invention may be carried out, 10 represents a tube threaded at one end to receive a compressing member 11. 12 indicates the packing member mounted on the tube, being positioned between the compressing member 11 and a member 13, the latter being held against movement; the member 13 may be considered, for the purpose of explaining the invention, as a fixed member. As shown, the members 11 and 13 are preferably provided with annular flanges which form recesses into which the ends of the packing extend. As will be readily understood, by threading

the member 11 inwardly, the distance between the members 11 and 13 will be decreased, thus expanding the member 12, with a tendency to form a space between the interior of the member 12 and the tube.

For the purpose of producing the zone or zones of substantially uniform resistance, I preferably employ one or more members 14 freely movable on the tube and having an outer surface preferably curved in cross section from top to bottom, these members being free to move on the tube excepting as such movement is restrained by reason of contact of the members with the packing member 12. These members 14 preferably have a normal position with respect to the packing member, this being produced by providing complementary annular recesses within the packing member in suitable manner. For instance, the packing member may be formed about the members 14, thus locating them as a part of the packing member for ready insertion on the tube, the members 14, however, not being fixedly positioned within the packing. Or, the interior of the packing member may be formed with grooves complementary to the members 14 and the latter afterward placed in position.

The number of members 14 which may be employed will depend upon the length of the packing member. In order to produce the desired result, I preferably employ at least two of such members within the packer.

With the parts assembled as indicated in Fig. 1, threading of the member 11 inwardly will tend to decrease the length of the packing member while expanding it. Since the members 14 are free to move on the tube, any material change in the direction of length of the packing member 12 will cause movements of the members 14 under the action of the walls of the recesses of member 12. Thus, when this compression action is had, its effect is immediate on the upper and lower ends of the packing member 12, tending to force the upper end of the packing member inwardly and thus providing pressure on the upper side of the top member 14; since the latter is unyielding, being preferably formed of metal, this action will tend to force this member downwardly and thus shift its point of greatest diameter downwardly, and tending to crowd the material of the packing outwardly at this point. This action also takes place in connection with the remaining members 14, tending to crowd the packing outwardly by attempting to shift the relative positions of the members 14 with respect to the walls of the recesses, the length of movement of succeeding members 14 decreasing, thereby producing a relative movement between members. While there might be a tendency to decrease the cross sectional width of the recesses or grooves under this compressing

action, the fixed configuration of members 14 prevents such action, so that there is also a crowding of the packing material between adjacent members 14, these members 14 shifting their positions in the directions of least resistance under the action of the packing member itself, thereby positioning the members 14 at such points as require the presence of the support, it being clear that if resistance to member-movements is equal on all sides of a member 14, the radial support for the packing material is complete, and at points where resistance to movements of a member 14 is less than at other points, the member will move in such direction until resistance again substantially equalizes, thus producing the zone of substantially equal resistance.

From the above, it will be understood that the members 14 have what may be considered a floating action with respect to the tube, and may be considered as floating ribs for the tube, even though they may be carried by the packing itself, as heretofore referred to.

The present invention may be applied to various uses, being particularly adapted for use in connection with well packers. For instance, in Fig. 3, I have shown it applied to a packer of the type disclosed in my companion application, filed March 5, 1915, Serial #12,301, the packer in this case being one set solely by rotation of a tool, the form shown being that of a packing plug at the bottom of a well, a position where the plug must retain its position independent of any weight and against the action of pressures. In this form, the packing member is set by the rotation of a threaded stem a working in a sleeve a' , this action causing the cap a^2 to be moved inwardly to compress the packing member, the fixed or opposing member being indicated at a^3 .

In Fig. 4, I have shown the invention as applied to a packer which is adapted to be set by the superimposed weight of the upper sections, a structure disclosed in the patent to P. H. and F. H. Mack, #1,145,155, July 6, 1915. In this arrangement, the packing member is set by the weight of the superimposed sections when the lower end of the packer reaches an abutment within the well. In this view, the fixed member is indicated at b and the movable member at b' .

While I have shown the application of the invention in connection with these two forms only, it will be obvious that it may also be employed in connection with other types.

What I claim is:

1. In combination, a tubular member, a packing member external of the tubular member and adapted to be set between opposing surfaces having a spaced distance greater than the thickness of the member,

- means for expanding the member by compression in the direction of member length, and rigid means loosely carried by the packing and rendered operative by the compressing action of the member for establishing substantially uniform resistance substantially throughout the length of the packing member.
2. In a well packer, a tubular body member, a compressible packing element embracing the body, means for compressing and expanding the packing, a plurality of rigid ring members loosely carried by the packing, said rings rendered operative to effect a wedging action by the compressing action of the packing for establishing substantially uniform resistance throughout the length of the packing.
3. In a well packer, a tubular body member, a compressible packing element embracing the body, means for compressing and expanding the packing, a plurality of rigid ring members loosely carried by the packing and disposed in contact with the body member, said rings rendered operative to effect a wedging action by the compressing action of the packing for establishing substantially uniform resistance throughout the length of the packing.
4. In packing structures for wells and in combination, a tubular member, a packing member external of the tubular member and adapted to be moved to packing position, means for expanding the packing member by a compressing action thereon, and rigid wedging means interposed between the packing and tubular members and freely movable with respect to the tubular member and the packing member for effecting a wedging action on and supporting the packing member in its expanded position.
5. In packing structures for wells and in combination, a tubular member, a packing member external of the tubular member and adapted to be moved to packing position, means for expanding the packing member by a compressing action thereon, and rigid wedging means interposed between the packing and tubular members and freely movable with respect to the tubular member and the packing member for supporting the packing member in its expanded position, said wedging means being movable toward each other and rendered active by the expanding action of the packing member.
6. In packing structures for wells and in combination, a packing member and its support, means for expanding the packing member by a compressing action, and a plurality of loosely mounted rigid wedging means interposed between the packing member and its support and movable in contact with and in the direction of length of the support by the compressing action of the packing for producing a substantially uniform resist-
- ance for the packing member substantially throughout its length.
7. In packing structures for wells and in combination, a packing member and its support, means for expanding the packing member by a compressing action, and loosely mounted rigid wedging means interposed between the packing member and its support and movable relatively to and in the direction of length of the support for producing a substantially uniform resistance for the packing member substantially throughout its length, the movement of said wedging means being controlled by the packing member.
8. In packing structures for wells and in combination, a packing member and its support, means for expanding the packing member by compression, and loosely mounted wedging means between the packing member and its support for supporting the expanded portion of the packing member, said wedging means being in the form of annular members freely movable with respect to the packing member support, and having portions loosely engaging the packing member, said wedging means rendered operative by the compressing action of the packing.
9. In combination, a packing member, a tubular member for normally supporting the packing member, means for compressing the packing member to increase its diameter, and wedging means between the packing and tubular members, said packing member having recesses on its inner periphery conforming to and adapted to receive the wedging means, said wedging means being in contact with the tubular member and rendered operative by the compressing action of the packing member.
10. In packing structures for wells, a packing member adapted to be expanded and having tubular recesses on its inner periphery, and a rigid wedging member for and loosely positioned within each recess, said rigid member being free to move relatively to said packing member.
11. In packing structures for wells, a packing member adapted to be expanded and having tubular recesses on its inner periphery, and a rigid wedging member for and loosely positioned within each recess, said rigid member being free to move relative to said packing member, said rigid member having an internal diameter approximating the normal internal diameter of the packing member.
12. In packing structures for wells, a packing member adapted to be expanded and having tubular recesses on its inner periphery, and a rigid wedging member for and loosely positioned within each recess, said rigid member being free to move relative to said packing member, said recesses having a configuration complementary to the

external configuration of the rigid members.

13. In packing structures for wells, a packing member adapted to be expanded and having tubular recesses on its inner periphery, and a rigid wedging member for and loosely positioned within each recess, said rigid member being free to move relative to said packing member, said rigid members each having its outer periphery curved in the direction of member axis.

14. In packing structures for wells, a packing member adapted to be expanded and having tubular recesses on its inner per-

iphery, and a rigid wedging member for 15 and loosely positioned within each recess, said rigid member being free to move relative to said packing member, said rigid members each having its opposite ends of least thickness, the recesses of the packing member corresponding in contour to the external contour of the rigid members. 20

In testimony whereof, I affix my signature in presence of two witnesses.
